UNITED STATES PATENT OFFICE

2,627,333

FRONT-FEED PAPER CARRIAGE CONSTRUCTION FOR ACCOUNTING AND THE LIKE MACHINES

Thomas M. Butler, Detroit, Mich., assignor to Burroughs Adding Machine Company, Detroit, Mich., a corporation of Michigan

Original application April 7, 1949, Serial No. 85,971. Divided and this application June 13, 1950, Serial No. 167,875. In Argentina April 13, 1949

4 Claims. (Cl. 197—128)

1

This invention relates to improvements in front-feed paper carriage constructions for accounting and the like machines.

An object of the invention is to provide an improved construction of power operated front-feed paper carriage.

A further object is to provide a paper carriage operable by power to adjust it from a normal working condition to an open-throat or front-feed condition and to return it to its normal closed or working condition and to provide means to prevent operation of the power means to return the carriage to normal condition when the carriage is not properly conditioned for such return.

A further object is to provide means to prevent an operation of the machine provided with such a carriage from being initiated while the carriage is being adjusted from its normal working condition to its open or front-feed condition.

A further object of the invention is to provide a carriage with a platen movable from a normal working or printing position to a retracted or open throat position and to provide means to decelerate and cushion the final portions of such movements of the platen.

Further objects and advantages of the invention will appear from the following detailed description referring to the accompanying drawings in which:

Fig. 1 is a perspective view of the assembled machine enclosed in its casing as seen from a point forwardly, above and to the right thereof;

Fig. 2 is another perspective view of the assembled machine enclosed in its casing as seen from a point above, rearwardly and to the right thereof;

Fig. 3 is a spread perspective of portions of the paper carriage as viewed from a point forwardly, rightwardly and above;

Fig. 4 is a partial section of the paper carriage and shows certain elements of the machine for operating the paper carriage and elements controlled by the paper carriage as viewed from the right;

Fig. 5 is a detail of the line-spacing mechanism;

Fig. 6 is a front elevation of the paper carriage in opened condition;

Figs. 7 and 8 are details of the form-heading holder;

Fig. 9 is an axial vertical section of the platen twirler clutch and neighboring elements on the platen shaft;

Fig. 10 is a fore-and-aft vertical section 55

2

through the paper carriage just inwardly of the right-hand carriage frame end plate and looking leftwardly, the carriage being in opened condition;

Fig. 11 is a view similar to Fig. 10 but omitting some of the parts and showing others of the parts in moved position;

Fig. 12 is a fore-and-aft vertical section through the platen frame omitting the platen and platen mounting parts;

Fig. 13 shows some of the parts of Fig. 12 in moved position;

Figs. 14 and 15 show the platen, platen frame, paper chutes and other paper guide elements in fore-and-aft vertical section as seen from the right;

Figs. 16, 17 and 18 are details of adjustable guides and stops for front-fed papers;

Fig. 19 is a detail perspective of a front-feed paper chute member;

Fig. 20 is a perspective of a portion of one of the paper guide members;

Fig. 21 is a bottom plan view of one of the lower journal pressure rollers and supporting means therefor;

Fig. 22 is a top plan view of a pressure roller assembly for front-fed papers;

Fig. 23 is a top plan view of a paper carriage operating power transmission drive unit herein-after referred to as the "gear box" together with various control parts mounted thereon;

Fig. 24 is a horizontal section through the lower part of the gear box;

Fig. 25 is a perspective view of certain carriage control keys and associated control parts;

Fig. 26 is a detail;

Fig. 27 is a spread perspective of control elements associated with the gear box and involved in controlling carriage movements, opening and closing of the carriage, and line-spacing;

Fig. 28 is another perspective including certain of the elements of Fig. 27 and additional control elements involved in the control of the carriage;

Fig. 29 is a laterally expanded perspective of the carriage opening and closing drive means and control means associated therewith;

Fig. 30 is a perspective of certain elements associated with the carriage opening and closing drive means and controlling the motor-starting switch;

Figs. 31 and 32 illustrate the construction of the clutches coupled in the carriage opening and closing and platen line-spacing drives;

Fig. 33 illustrates the engaging and disengag-

ing control means for the carriage opening and closing drive clutch;

Fig. 34 illustrates the engaging and disengaging control means for the line-spacing drive clutch;

Fig. 35 is a spread perspective of certain interlock means associated with the carriage opening and closing drive means and with the control means for the main drive clutch of the machine;

Fig. 36 is a perspective view of portions of the control means for the line-spacing drive clutch; and

Fig. 37 illustrates an interlock means associated with the line-spacing drive, with the carriage opening and closing control and with the machine cycling control.

The illustrated calculating and accounting machine is that disclosed in full detail in my copending application Serial No. 174,696, filed July 19, 1950, as a continuation-in-part of my prior application Serial No. 85,971, filed April 7, 1949, since abandoned, of which the present application is a division. Other divisional applications are Serial No. 181,401, filed August 25, 1950, Serial No. 196,844, filed November 21, 1950, Serial No. 252,713, filed October 23, 1951, Serial No. 278,260, filed March 24, 1952, and Serial No. 282,843, filed April 17, 1952. Only those structures and mechanisms of the machine with which the present invention is concerned will be described in detail herein. To provide for simple and easy identification of corresponding elements of both disclosures, the parts illustrated and described herein are designated by the same reference numbers as in the abovementioned copending application.

Throughout the following description, consistently with the description in the above-mentioned copending application, the words clockwise and counterclockwise will be used to describe positions and motions of elements of the machine as seen by an observer in front of, at the right, or above the moving parts in the positions in which they are located in the machine. The words right, rightward, left and leftward will be employed to describe positions and motions as seen by an observer in front of the machine. The words above, up, upward, below, down, downward, front, forward, rear, rearward, and behind will be employed to describe positions and motions as they occur in the machine when it is in its normal upright position.

As disclosed fully in the above-mentioned copending application, the machine is a key-set, electric motor-driven machine adapted for a great variety of accounting, bookkeeping and other work involving calculation. It has a traveling front-feed paper carriage into which record material and work papers may be inserted from the front. Operation of the machine may be initiated manually by depression of various motor bars and "live" function control keys on the keyboard or automatically by automatic function control means operating in accordance with the columnar positioning of the paper carriage. Certain of the motor bars as well as the automatic function control means also control operations of the paper carriage and parts thereof.

As will be disclosed in detail herein, the paper carriage supports a platen which is movable from its printing position to a retracted or front-feed position and reversely. Elements cooperating with the platen to form a front-feed paper throat are automatically adjusted to open-throat position when the platen is retracted from printing position and automatically restored to closed-

throat position as the platen is returned to printing position. The opening and closing of the carriage, that is, the movements of the platen from printing to retracted or front-feed position and reversely as well as the adjustment of the throat-forming elements to their open and closed-throat positions are effected by power derived from the machine drive motor independently of the columnwise movement or non-movement of the paper carriage and transmitted through direct drive connections which are effective independently of the cycling of the machine. The control of the opening and closing of the carriage can be effected automatically during machine operation as well as manually through a key on the keyboard without cycling the machine. Initiation of machine cycling is prevented while the carriage opening and closing key is depressed, while the carriage is opening, and while the carriage is not in proper condition for automatic closing. Depression of the carriage opening and closing key is prevented while the machine is cycling and while the carriage is open and not in proper condition for closing.

The front-feed construction of the carriage is of an improved form providing for very easy and rapid insertion, alignment and removal of record material and work sheets. The paper guides are adapted to rapid and easy change-over to accommodate the changes in paper sizes which may be required when changing from any program of work to any other program of work to be performed on the machine.

PAPER CARRIAGE

Carriage frame and mounting

The carriage 1056 is supported on a movable race member 1061 (Fig. 3) having front and rear rail members with V-grooves 1060 and 1063 and tied together in parallel spaced relation by laterally spaced connecting portions. The race member 1061 is supported for movement crosswise of the machine by two lines of bearing rollers 1038 received partly in the grooves 1060 and 1063 and partly in facing V-grooves in race rails 43 and 44 (Fig. 10) which are mounted on the machine frame as disclosed in the above-mentioned copending application with small roller-retaining plates 1071 (Figs. 1 and 2) secured on their ends.

The right and left carriage frame end plates 1069 and 1070 respectively (Fig. 3) have the forward parts of their lower edge portions secured to the respective ends of the movable race member 1061 by headed screws passing through the plates 1069 and 1070 and threaded into the ends of the front and rear race rails of the member 1061. The plates 1069 and 1070 are also braced and tied together by a rear cross rod 1072 (Figs. 2 and 3) having at each end a reduced portion (not shown) threaded into the inward end of a post 1073, the outer end of which is secured to the respective side plate 1069 or 1070 by means of a headed screw threaded into the post through the side plate. The plates 1069 and 1070 are further braced and tied together by a guide supporting member 1074 (Figs. 2, 3, 4 and 10) against the ends of which the plates 1069 and 1070 are secured by pairs of headed screws passing through the respective plates and threaded into the ends of the member 1074.

A light coverplate 1075 extends across the lower portion of the front of the carriage and has, at its upper corners, ears secured, as by screws, to the side plates 1069 and 1070. The

lower portion of the plate 1075 is bent rearwardly and at the lower rear ends of its side, has lugs 1076 (Fig. 4) which extend laterally into notches 1077 (Fig. 3) cut into the forward end portions of the lower edges of the plates 1069 and 1070.

The carriage may be driven in either the tabulating or the return direction, that is, either leftwardly or rightwardly by a means, described in detail in the above-mentioned copending application, geared to a rack bar 1078 (Figs. 3 and 4) which extends longitudinally the full length of the carriage and is secured to the underside of the movable race member 1061 by a plurality of headed screws passing upwardly through the rack bar 1078, then through spacing collars 1079 seated against the underfaces of bosses on the underside of the member 1061 and then into threaded bores in the latter member.

Platen and platen frame

The roller platen 1057 is provided at its ends with hubs 1080 (Figs. 6 and 9) secured, as by means of set screws, on a shaft 1081 which is journaled in bushings 1082 spun into two plates 1083. Axial movement of the platen shaft 1081 in the bushings 1082 is prevented by a spring clip 1084 engaging in a circumferential groove in the shaft 1081 immediately at the right of the right-hand bushing 1082 and by a spacing sleeve 1085 which surrounds the shaft 1081 between the left-hand bushing 1082 and the hub of the left-hand one of two similar twirlers 1086 which are secured, as by set screws, on both outer ends of the platen shaft outwardly of the carriage end plates 1069 and 1070. Each plate 1083 is pivotally supported on a headed screw 1087 (Figs. 3 and 11) which passes through an ear extending from the lower side of the plate 1083 and is passed through the adjacent one of two platen frame end plates 1088 where it is secured by a nut. In its upper portion, each plate 1083 has a slot 1089 elongated in an upward and downward direction. The front and rear edges of the slot 1089 engage an eccentric portion of a stud 1090 which is rotatably fitted in the adjacent end plate 1088 and has a hexagonal head on one end and a nut threaded on the other end so that by rotating the studs 1090, the platen 1057 may be adjusted relatively to the plates 1088 toward or away from the type bars 562 (Fig. 4) to secure the desired strength of impression on papers supported on the platen. By tightening the nuts upon the studs 1090, the parts may be secured in adjusted position.

The platen frame end plates 1088 are secured to collars 1091 pinned on a shaft 1092 which is journaled in bushings spun into the carriage end plates 1069 and 1070. The collars 1091 abut the inner sides of the bushings to prevent endwise movement of the platen frame within the carriage frame. The plates 1088 are also tied together and braced by a V-section channel member 1093 (Fig. 14) having on each side at each end a turned-over lug secured to the adjacent plate 1088 as by a headed screw and nut. The plates 1088 are further tied together and braced by a member 1094 of inverted channel section having at each end of its front rear sides a turned-over ear which is secured against the inner side of the adjacent end plate 1088 as by a headed screw and nut. When the platen frame is in its normal position, outwardly turned lugs 1095 on the lower front portions of the end plates

1088 rest on the upper side of the front race rail of the race member 1061.

Rocking platen frame from printing position to front-feed position and reversely

To facilitate the insertion of papers from in front of the platen, as will be explained in detail hereinafter, the platen frame may be rocked clockwise about the axis of the shaft 1092 to move the platen 1057 rearwardly from its normal printing position and returned counterclockwise to return the platen forwardly to its normal printing position. For this purpose, a bail member 1096 (Figs. 3 and 4) extending transversely of the machine substantially from end to end of the carriage is supported to swing forwardly and rearwardly beneath the race member 1061 by a plurality of arms 1097 extending upwardly between the race rails of the member 1061 and secured at their upper ends in flattened seats on a platen frame rocking shaft 1098 journaled near its ends in bushings spun into the carriage end plates 1069 and 1070.

Arms 1099 secured at their lower forward ends to hubs pinned on each end of the shaft 1098 have in their upper rear ends longitudinally elongated slots each embracing a roller stud 1100 secured in the lower forward end of a respective one of two arms 1101. Each arm 1101 is secured on a hub pinned on the outer end of a respective one of two shafts 1102 each journaled in a bushing 1103 secured in the respective carriage end plate 1069 or 1070. Each of two cam arms 1104 is secured on a hub pinned on the inner end of a respective one of the shafts 1102 and each has a cam slot embracing a roller 1105 rotatable on a stud secured in the rear portion of the adjacent one of the platen frame end plates 1088. The cam slot in each cam arm 1104 has an upper rear and lower front dwell portion concentric with the shaft 1102, the lower front dwell portion being at the greater radius from the axis of the shaft 1102, and an inclined portion connecting the two dwell portions.

When the bail 1096 is swung forwardly, the cam arms 1104 are swung downwardly pulling the rollers 1105 and platen frame rearwardly about the shaft 1092 to retract the platen 1057 rearwardly from its printing position. When the bail 1096 is returned rearwardly, the platen frame and platen are returned forwardly to printing position. The means for swinging the bail 1096 will be described in detail hereinafter. The openings in the carriage end plates, through which the ends of the platen shaft 1081 extend outwardly, are elongated arcuately about the shaft 1092 to accommodate the swinging movement of the platen shaft as the platen frame is swung about the shaft 1092.

Journal pressure rolls

Three upper journal pressure rolls 1106 (Figs. 6, 11 and 15) are rotatably supported on a shaft 1107 secured to two arms 1108 and 1109 by headed screws passing through the arms and threaded into the ends of the shaft. The arms 1108 and 1109 are pivotally supported on studs 1110 secured in rearward extensions of the upper ends of the platen frame end plates 1088. A plate 1111, extending from side to side of the assembly, is secured near its two rear corners to ears turned inwardly from the rear upper edges of the arms 1108 and 1109 and has at its front a downwardly turned flange which, at its opposite ends, is secured to inwardly turned front end portions of

the arms 1108 and 1109. The rearward edge of the plate 1111 may serve as a tear-off blade for continuous roll journal paper passing around the platen and preferably, for that purpose, is serrated.

The arms 1103 and 1108 and plate 1111 together provide a rigid swingable support for the shaft 1107 which, on opposite sides of the middle pressure roller 1106, also passes through two short side arms of a yoke 1112 (Figs. 6 and 15) which engages against the plate 1111. Tension springs 1113 (Figs. 10 and 11) secured at their upper ends to studs in the respective arms 1103 and 1109 and at their lower ends to studs secured in the respective left and right-hand plates 1088 normally urge the rollers 1106 downwardly against the platen 1057. A rearward extension of the arm 1108 carries a roller stud 1114 (Figs. 4, 10 and 11) through which the arms 1108 and 1109, plate 1111, shaft 1107 and rollers 1106 are swung away from the platen, as will be described in detail hereinafter.

Each of a plurality of lower journal pressure rollers 1115 (Figs. 10, 12, 13, 14, 15 and 21) is mounted on an individual short shaft 1116, each of the ends of which is guided between a pair of downwardly turned lugs of a mounting bracket 1117 secured to the lower side of a journal guide plate 1118. The rollers 1115 are urged upwardly to press against the platen 1057 through openings in the plate 1118 by leaf springs 1119 which at their forward ends press upwardly against the ends of the shafts 1116 and at their rear ends are secured to the brackets 1117. Rearwardly of the line of rollers 1115, the plate 1118 is secured to the flattened side of a shaft 1120, the ends of which are journaled in the platen frame end plates 1088.

An arm 1121 (Figs. 12 and 13) secured on the left end portion of the shaft 1120 is connected at its rear end to the lower end of a tension spring 1122 which is connected at its upper end to the upper rear arm of a lever 1123 rockably mounted on the shaft 1120 on the left side of the arm 1121. The arm 1121 also has a projection 1124 which the spring 1122 normally holds yieldingly engaged against the underside of a stud 1125 secured in the upper rear arm of the lever 1123. A tension spring 1126 connected at its forward end to a stud secured in the left-hand plate 1088 and at its rear end to the forward lower arm of the lever 1123 urges the latter and thus also the lever 1121 and shaft 1120 clockwise whereby the rolls 1115 are normally yieldingly urged against the platen 1057.

A finger lever 1127 is formed on the left side of a yoke pivoted on a stud 1123 threaded into a larger diameter stud secured in the left-hand carriage frame end plate 1070 from the right-hand side thereof, and a cam arm 1129 is formed on the right-hand side of the yoke. The parts are so proportioned and arranged that when the lever 1127 is rocked rearwardly, while the platen frame is in its rearward position, the cam arm 1129 will cam forwardly a stud 1130 carried by the upper rear arm of the lever 1123 whereby the levers 1123 and 1121 and the shaft 1120 may be rocked counterclockwise to lower the rollers and forward part of the plate 1118 away from the platen. The end of the cam arm 1129 is formed with an arcuate edge concentric about the stud 1123 so that, when the end of the cam arm is moved upwardly behind the stud 1130 and the yoke is stopped by the member 1074 as shown in Fig. 13, the arm 1129, until manually returned,

will remain in such roller-retracting position despite the tension of a light spring 1131 which is connected between studs secured in the lever 1127 and in the carriage end plate 1070, respectively, and which normally holds the lever 1127 in its forward position. The rollers 1115 and the forward portion of the guide plate 1118 are thus releasably held in the lowered position of Fig. 13. It will be apparent that either by pulling the lever 1127 slightly forward or upon returning the platen frame forwardly to its normal position, the parts are released for return to normal by the springs 1126 and 1131.

Holding means for front-fed papers

It will be apparent that the two lines of pressure rollers 1106 and 1115 are well suited to maintain feeding engagement between the platen 1057 and papers, such as a journal sheet and a carbon paper, or the like, overlying the journal sheet, which are to remain in the carriage, throughout a succession of posting operations. However, it is desirable that other means be provided for releasably holding against the platen other papers, such as ledger and/or statement forms, which are to receive only one or a few lines of entries at a given time and then removed and replaced by similar papers which also are to receive only one or a few lines of entries before being removed and replaced by further similar papers. For that purpose, there is provided a line of pressure rollers 1132 (Figs. 6, 10, 12, 13, 14 and 15) supported in the platen frame.

About midway of the length of the platen 1057 and near each end of the platen there is (Fig. 6) a longer roller 1132 and between the longer rollers 1132 there are pairs of shorter rollers 1132. Each longer roller 1132 is rotatable on an individual short shaft 1133 and both rollers 1132 of each pair of short rollers are rotatably supported on another similar shaft 1133. Each shaft 1133 is supported in the forward ends of a pair of arms 1134 (Figs. 12 and 22) pivotally supported at their rear ends on a short shaft 1135. The shaft 1135 is supported at its ends in a pair of small plates 1136 which are staked in upright positions in the flat upper portion of the channel member 1094. Spring clips 1137, engaged in circumferential grooves in each shaft 1135 adjacent the facing sides of the arms 1134, hold the shafts 1135 against endwise movement. Between each arm 1134 and the adjacent plate 1136, a lever 1138 is pivotally mounted on the shaft 1135. A lower arm of the lever 1138 is held in engagement against the shaft 1093 (Figs. 3, 6 and 12) by a tension spring 1139 (Figs. 12 and 22) which is connected at its upper end to the upper forward arm of the lever 1138 and at its lower end to a laterally bent portion of a downward projection of the arm 1134 whereby the springs 1139 also urge the rollers 1132 against the platen 1057.

Opening front-feed throat

When the rockable platen frame and the platen 1057 are in their normal position (Fig. 4), the springs 1139 hold the pressure rolls 1132 yieldingly pressed against such papers as may be positioned in the throat between them and the platen with sufficient pressure to insure certain and accurate line-spacing of the forms by rotation of the platen. As the platen frame rocks rearward toward the front-feed position (Fig. 12), second laterally bent portions 1140 (Figs. 6, 12 and 22) of the downward projections of the arms 1134 engage and are arrested by rearwardly

bent hooks 1141 on the upper edge of a front-feed throat-opening control member 1142 extending across the width of the carriage frame and having on the lower portions of its ends small stud-like portions by which the member 1142 is pivotally mounted in the carriage end plates 1069 and 1070. Intermediate its ends, the member 1142 is rockably supported in two brackets 1143 (Figs. 4, 6 and 11) secured to the upper side of the front race rail of the member 1061. As the platen frame and platen complete their movement rearwardly to front-feed position, the platen 1057 moves away from the arrested pressure rolls 1132 to open the throat between them to permit quick and easy removal of previously front-fed papers and the front-feeding of the papers to receive the next entries.

To cause the front-feed paper throat between the pressure rollers 1132 and the platen to remain closed as the platen is thrown back, or to release the rollers 1132 to move against the platen after the carriage has been opened and while the platen remains in its rearward position, the operator may push rearwardly the upper end of a lever 1144 (Fig. 10) pivoted on a stud secured in the left-hand carriage frame member 1070 to cause the lower end of the lever to engage the end of the upper left-hand end portion of the member 1142 and swing it forwardly to disengage the hooks 1141 from the arms 1134.

Accelerating and decelerating movement of platen

It should be noted that as the platen frame rocks rearwardly about the shaft 1092 and carries the shafts 1135 with it, the levers 1138 are permitted to rock counterclockwise on the shafts 1135 relative to the platen frame, thereby reducing the tension of the springs 1139 to a very light tension and somewhat assisting the movement of the platen frame, until the hooks 1141 arrest the levers 1134. Thereafter, the final rearward movement of the platen frame increases the tension of the springs 1139 which thus check the final rearward movement of the platen frame and reduce the shock of arresting the platen frame in its front-feed position. When the platen frame is again swung forwardly toward printing position, the initial forward movement of the platen frame and platen is accelerated by the springs 1139, the tension of which is again reduced to a very light tension before the papers are again gripped between the platen 1057 and rollers 1132. Subsequently, as the supporting arms 1134 for the rollers 1132 are moved away from the hooks 1142 and the levers 1138 are rocked clockwise as the shafts 1135 swing further downward toward the shaft 1098, the tension of the springs 1139 is again increased to a value sufficient that the papers will be firmly pressed against the platen to insure certain and accurate line-spacing by rotation of the platen.

The retensioning of the springs 1139 as the platen 1057 moves the rollers 1132 again to their normal positions also checks the final portion of the return movement of the platen and platen frame to printing position and thus reduces the shock of arresting the platen and platen frame in the normal printing position. Also, although the pressure rolls 1132 normally press against the platen with sufficient pressure to avoid danger of slipping of any papers between the pressure rollers 1132 and the platen, yet when the pressure rollers 1132 initially grip the papers between them and the platen as the throat is closed dur-

ing the movement of the platen from its front-feed position to its printing position, the tension of the springs 1139 is very light so that the production of carbon smudges, which occurs when a platen and pressure rollers are brought together under heavy spring tension, is safely avoided.

Means to hold front-fed papers in open throat

10 When papers such as ledger cards and statement forms are front-fed into the carriage, the gentle bending of such papers by certain portions of the carriage structure, as hereinafter pointed out in detail, is generally sufficient to cause sufficient frictional hold on the papers to keep them in the positions in which they are manually placed while the carriage is open, that is, while the platen is in its front-feed position and the pressure rollers 1132 are held away from the platen. It is, however, desirable to provide additional means to give additional insurance of the papers being held in the desired positions until the carriage is closed, that is, until the front-fed papers are positively gripped between the platen and pressure rollers 1132.

15 The two rollers of each pair of small rollers 1132 are spaced apart on their shaft 1133 (Figs. 6 and 22) and the forward portion of one of two light pressure fingers 1145 is located between them. Each of the fingers 1145 has, on both of its sides near its rearward end, downwardly turned ears which are pivotally supported on the shaft 1135 which supports the two arms 1134 for the respective pair of small rollers 1132. The forward portions of the fingers 1145 are bent upwardly and again forwardly to provide rounded contact portions to be pressed against papers inserted between them and the platen. Springs 1146 (Figs. 12-15) connected at their lower ends to laterally bent lower ends of lugs 1147 bent downward from each of the fingers 1145 and connected at their upper ends to the shafts 1133 between the small rollers 1132, urge the contact portions of the fingers 1145 against the platen. These light pressure fingers 1145 remain normally pressed against papers which are between them and the platen, not only when the carriage is closed and the platen is in printing position but also when the platen is in its front-feed position and the carriage is open for the front-feeding of papers.

20 It will be apparent that if, for example, a ledger card and statement form are inserted side by side, each will be lightly frictionally held against the platen in the position in which it is manually inserted. However, when a new journal sheet is to be inserted in the carriage, it is desirable to retract the fingers 1145 from the platen. For that purpose, each finger extends rearwardly over a shaft 1148 (Figs. 12-15 and 22) which is rotatably supported in the rear portions of the plates 1136 and is formed under the rear end of each finger 1145 with a flattened side normally positioned to permit the finger to be spring-pressed against the platen. At its end adjacent the left-hand platen frame end plate 1088, the shaft 1148 has secured on it a lever 1149 (Figs. 12 and 13) having a lower arm passing through a slot in the upper part of the channel member 1094 and normally engaged against the front face of the rear side portion of the member 1094. An upper arm of the lever 1149 carries a stud 1150 engaged in a slot in a lower arm of the lever 1123 so that, when the lever 1127 is moved rearwardly to lower the journal pressure rollers 1115

and guide plate 1118 away from the platen to permit the insertion of a journal sheet about the platen, the shaft 1098 is rocked clockwise and cams the rear ends of the fingers 1145 upwardly to lower their forward ends away from the platen.

Paper guide means

An inwardly extending stud 1151 (Figs. 3, 4 and 10) is secured in each of the carriage frame end plates 1069 and 1070. Each stud 1151 rotatably supports a hub or sleeve 1152 on the inner end of which an arm 1153 is secured. Each arm 1153 rotatably supports a headed shouldered screw 1154 threaded into the respective end of a guide supporting member 1155 extending between and a little beyond the ends of the platen 1057. In each end of the member 1155, a second screw 1156 is threaded, the head thereof being positioned in an arcuate slot formed in the upper end of the adjacent arm 1153 and centered on the axis of the screws 1154. The screws 1154 and 1156 at each end of the member 1155 also pass through arms 1157 which they secure to the respective ends of the member 1155. The member 1155 and the arms 1157 are thus supported in the arms 1153 for pivotal movement about the axis of the screws 1154 limited by the length of the slots in which the screws 1156 move.

Two springs 1158 (Fig. 4), each connected at its forward end to a respective one of the arms 1157 and at its rearward end to the respective arm 1153, urge the arms 1157 and member 1155 counterclockwise to maintain a roller 1159, supported on a stud eccentrically adjustably mounted in the lower end of each arm 1157, normally in engagement with the forward edge of the respective plate 1083. The forward edges of the plates 1083 are so shaped as to position the member 1157 and the hereinafter described paper guides carried thereby, in an unobjectionable position when the platen and platen frame are in printing position and in the desired positions relative to the surface of the platen, when the platen frame is in its front-feed position. The shape of the forward edge of each plate 1083 is also such as to cause the rollers 1159 to rock the member 1155 and parts carried thereby so that they will not bear against papers which are between them and the platen as the platen and platen frame are moved from front-feed position to printing position and reversely.

Front-feed guide chutes for papers, such as ledger and statement forms, are supported on the member 1155. Each such chute comprises a pair of members 1160 (Figs. 1, 2, 4, 10 and 19) each having a portion extending downwardly across the front face of the member 1155 and another portion extending downwardly behind the upper portion of the member 1155. Knurled thumb-screws 1161 pass through the rear portions of the members 1160 and are threaded into T-section clamping blocks 1162 inserted in a rearwardly opening T-section channel 1062' (Figs. 2, 3 and 4) running from end to end of the member 1155 in the upper portion thereof. The front portion of each member 1160 has on the lateral edge thereof remote from the other member 1160 of the pair, a forwardly extending flange 1163. Each member 1160 supports a member 1164 having side portions adjustably clamped to the forwardly bent flange 1163 by a screw and nut passing through an elongated slot in the flange 1163. At their fronts, the members 1164 have upwardly widening and downwardly narrowing flanges extending

toward each other at substantially right angles to their side portions.

When the thumb-screws 1161 are loosened, the members 1160 and the members 1164 carried thereby may be moved laterally along the support 1155 to separate the two members 1164 of each front-feed paper chute to suit the papers to be front-fed through the chute, after which the thumb-screws 1161 may be tightened to secure the two side assemblies of the chute in the proper position. Additional adjustable T-blocks 1165 (Fig. 2) may be secured in desired positions in the channel in the member 1155 to provide limits against which the operator may quickly position the clamping blocks 1162 when changing over from work involving one set of forms to work involving another set of forms of different widths.

Normally, that is, when the platen and platen frame are in printing position, the chute members 1164 are held positioned above and a little to the rear of the front of the platen 1057 where they will not interfere with the operation of the type bars 562 (Fig. 4) but, nevertheless, hold the upper portions of the front-fed papers therein substantially vertical. Each of the sleeves or hubs 1152 secured to the arms 1153 has also secured on it a downwardly extending arm 1166 (Figs. 3, 4, 10 and 11) carrying at its lower end, a stud 1167 normally engaged in an upwardly open notch in the rear end of a link 1168 pivoted on a stud secured in the upper end of a short arm 1169 secured to a hub pinned to the shaft 1098 adjacent the inner side of the respective carriage frame end plate 1069 or 1070. A tension spring 1170 connected between a stud in an upper forward extension of the link 1168 and a stud secured in the adjacent end plate 1069 or 1070 normally holds the notched rear end of the link 1168 in latching engagement with the stud 1167 to hold the arms 1153, the chute supporting member 1155 and the chutes carried thereby in the desired normal positions.

As the bail 1096 is swung clockwise to rock the platen frame to its front-feed position, the arms 1169 first shift the links 1168 rearwardly and swing the arms 1166 and 1153 counterclockwise relative to the platen frame to lower the bottom ends of the paper chutes toward the front of the platen. The studs 1169 follow the front edges of the plates 1083, swinging the member 1155 and the chutes carried thereby about the axis of the screws 1154. Then, during the latter part of the clockwise rocking of the bail 1096, a lower forwardly extending finger of each link 1168 engages the hub of the associated arm 1169 and causes the links 1168 to swing clockwise with the arms 1169 and shaft 1098, thereby lowering the notched rear ends of the links 1168 out of engagement with the studs 1167. The arms 1166 and thus the arms 1153 are held against further counterclockwise movement by engagement of the arms 1166 against the studs 1171 (Fig. 10) secured in the adjacent carriage frame side plates 1069 and 1070.

The operator may then remove any previously front-fed papers by pulling them upwardly out of the chutes and then front-feed new papers, lower end first and downwardly, through the chutes 1160, 1164, which guide the papers at each side. The lower end of a paper being front-fed passes between the platen 1057 and the pressure rollers 1132 and rearwardly of one or both of the fingers 1145 after which it is guided by a plate 1172 (Figs. 10, 14 and 20) into a rear paper chute described hereinafter. The plate 1172 is

secured, as by countersunk screws, to a flattened side of the shaft 1092 (Fig. 14) and has, at each side, an upwardly bent ear secured by a screw to the adjacent one of the platen frame side plates 1088. The forward part of the plate 1172 is notched to accommodate the pressure rollers 1132 in their movement toward and away from the platen. The front and side edges of the plate 1172 are bent downwardly somewhat to stiffen the plate and the rear edge is turned up to form a stop for front-fed paper when the rear paper chutes, next described, are not used.

The rear paper chutes form part of an assembly that is readily removable from the carriage and replaceable by a similar assembly adjusted for paper forms of different size. On each end of a transverse supporting bar 1173 (Figs. 2, 10 and 16) a plate 1174 is secured by means of a pair of screws. The forward end of each plate 1174 has a forwardly opening notch to receive a respective one of two supporting studs 1175 each extending inwardly from the respective carriage end plates 1069 and 1070 to which it is secured by a flanged stud 1176 (Fig. 4) having a shank passing through that carriage end plate and threaded into the stud 1175. Each plate 1174 has on the rearward portion of its upper edge an upwardly and then forwardly extending projection 1177 (Figs. 2 and 4) adapted to hook on another stud 1178 secured in and projecting inwardly from the adjacent plate 1069 or 1070.

Each plate 1174 carries a stud 1179 pivotally supporting, on the inner side of the plate, a latch lever 1180 (Figs. 2, 4 and 10) having on its rear end a finger-piece by which it may be depressed. A spring 1181 is anchored on a stud 1182 (Fig. 10) secured in the plate 1174, passes upwardly and then rearwardly around the front and upper sides of a higher stud 1183 secured in the plate 1174, and has its rear end engaged under a stud 1184 secured in the latch lever 1180 rearwardly of the pivot axis of the latter. The spring 1181 urges the latch lever 1180 counterclockwise to yieldingly hold the bottom edge of an upwardly opening notch, formed in the latch lever forwardly of the finger-piece thereof, engaged against the stud 1178 to releasably hold the plate 1174 against rearward movement relative to the studs 1175 and 1178. Pivotal movement of each latch lever is limited by a stud 1185 threaded into the respective plate 1174 and passing through a slot formed in the latch lever 1180 arcuately about its pivot center.

Each rear paper chute comprises a pair of guides 1186 (Figs. 2, 4, 10, 14, 16 and 17) each of which comprises a forwardly and rearwardly elongated plate or strip having its lateral edge portion 1187 remote from the other guide of the pair bent upwardly and then toward the other guide of the pair to form a channel to guide a lateral edge of the inserted paper. Each guide 1186 has secured to its underside, as by spot-welding, a front bracket 1188 (Fig. 16) and a rear bracket 1189. The front bracket 1188 extends downwardly in front of and then rearwardly under the front edge of the supporting bar 1173 and the rear bracket 1189 has a portion bent downwardly behind the rear edge of the supporting bar 1173. The downwardly bent portion of the bracket 1189 has two side portions 1190 which are bent forwardly under a flange left on the upper rear side of the supporting member by the formation of a rearwardly opening T-sectioned channel running from end to end of the rear portion of the supporting member 1173. 75 1205.

A central part 1191 of the downwardly bent portion of the rear bracket 1189 extends straight downwardly across the open slot of the T-channel in the supporting member 1173. A piece 1192 of resilient material, such as felt, is secured to the surfaces of the guide 1186 and brackets 1188 and 1189 around the supporting member 1173 to permit of easy lateral sliding of the guide and brackets laterally along the support 1173.

10 A clamping block or shoe 1193 (Figs. 10 and 16) is slidable in the wide portion of the T-channel in the member 1173 and rigidly carries a stud 1194 which extends rearwardly through the narrow opening in the channel, through the central part 1191 of the downwardly bent portion of the bracket 1189, through a sleeve 1195, and through a notch in a bracket 1196 which is secured to the bracket 1189 and holds the sleeve 1195 against axial movement. A pinion 1197 is secured upon a hub 1198 (Fig. 10) which is circumferentially grooved to receive the edges of the bracket 1196 about the notch therein and is threaded onto the rear end of the stud 1194. The pinion 1197 meshes in a ring of apertures formed in a knurled disk 1199 rotatably carried on a stud 1200 secured in the rear portion of the bracket 1189. A pair of nuts, threaded on the stud 1194 behind a washer separating them from the pinion 1197, prevent the latter from running off of the stud.

30 The disk 1199 is of a diameter greater than the width of the guide 1186 and bracket 1189 so that the operator's fingers may grasp it from above the guide 1186 to rotate it and thereby rotate the pinion 1197 and its threaded hub 1198 on the stud 1194. Counterclockwise rotation of the pinion 1197 (clockwise as viewed in Fig. 16) draws the stud 1194 and shoe 1193 rearwardly to clamp the flanges of the member 1173 along the T-channel between the shoe and the downwardly bent portion of the bracket 1189 to secure the guide 1186 in any position of lateral adjustment on the supporting member 1173 as required by the width and the desired position of papers being handled.

45 The front ends of the lower part of each guide 1186 are positioned in a depression 1201 (Figs. 14 and 15) formed in the upper side of the plate 1172 from side to side thereof to prevent the lower edge of a paper being front-fed from catching on the front ends of the guides 1186 as the paper is guided by the plate 1172 to the guides 1186.

50 55 Each guide 1186 is provided with an adjustable paper stop (Figs. 2, 17 and 18). The paper stop comprises a spring-metal stop plate 1202 lying on the upper face of the lower portion of the guide 1186 and having three forwardly extending fingers having downwardly bent stop lugs 1203 in a common plane substantially normal to the upper face of the guide 1186. The middle forward finger of the stop plate 1202 is bent upwardly further than the other two fingers and its downwardly bent stop lug 1203 extends downwardly slightly into a forwardly and rearwardly extended, closed slot 1204 in the guide 1186.

60 65 70 On top of the rear portion of the stop plate 1202 is a cam plate 1205 having front and rear lugs 1206 extending downwardly through, respectively, an aperture 1207 and a notch 1208 in the plate 1202 and into the slot in the guide 1186. The lugs 1206 both have sliding contact with one edge of the slot in the member 1173 to prevent turning of the plate 1202 as well as of the plate

On top of the cam plate 1205 is a lever 1209 having two downwardly pressed frustro-conical cam projections 1210 adapted to register with two frustro-conical raised cam portions 1211 on the upper face of the plate 1205. A clamping plate 1212 located under the guide member 1186 is secured to the lower end of a stud 1213 which passes upwardly through the slot in the member 1186 and registering openings in the plates 1202 and 1205 and lever 1209. The upper end of the stud 1213 is flattened on opposite sides to provide shoulders to support a washer 1214 and also provide a non-circular portion within a correspondingly shaped aperture in the washer to prevent the washer from turning on the stud after the parts are secured together in assembled relation by a headed screw threaded into the upper end of the stud 1213.

When the lever 1209 is turned counterclockwise from its position of Fig. 17 to place the cam portions 1210 out of alignment with the cam portions 1211 of the plate 1205, the stop is freely slideable forwardly and rearwardly on the guide 1186. When the lever 1209 is returned clockwise to its position of Fig. 17, the cam portions 1210 of the lever 1209 ride up on the cams 1211, forcing the plates 1205 and 1202 downward and pulling the plate 1212 upward to clamp the edges of the guide 1186 between the plates 1202 and 1212 to secure the stop in adjusted position on the guide 1186. The rocking of the lever 1209 is limited by a flange turned up from one of the side edges of the plate 1205.

When the forms inserted during a given work period are all to receive entries in the same line position, the stops 1202 may be positioned to stop the inserted papers with the desired line of the form at the printing line of the machine. If the line positions of entries on successively inserted forms vary, the stops may be positioned so as to permit each form to be inserted far enough to bring its top entry line to the printing line of the machine.

If, as will frequently be the case, the same machine is to be used to perform different kinds of work involving the use of forms of different sizes, instead of adjusting the rear paper guides 1186 on their supporting bar 1173 and adjusting the stops 1202 at the time of each change-over from one kind of work to another, a separate rear paper chute assembly may be provided for each set of forms to be used so that when it is necessary to change over from one kind of work to another, the operator may merely depress the latch levers 1180 and remove the supporting bar 1173 with the guides thereon rearwardly from the machine and then replace it with another assembly pre-adjusted to the set of forms to be used in the work to be done next. That not only saves time of the operator but avoids difficulty which may result from frequent adjustments which sometimes may be inaccurately made.

Line finder and form-heading holder

When successive front-fed papers must receive entries on different lines, the operator must manually adjust them to the proper line positions. The operator is aided to correctly position the front-fed papers by a line finder comprising a long relatively narrow plate 1215 (Figs. 1, 3, 6, 7, 8, 10, 11 and 13) bent to somewhat of an S-shape in fore-and-aft vertical section and staked at its ends in the arms 1157 with its upper edge at the lower ends of the chute members 1164 when the latter are in front-feed position. The paper being front-fed, as shown rather diagram-

matically in Fig. 14, will be lowered until the base line of the last previous line of entries thereon is positioned just above the upper edge of the line finder 1215 where the paper will be lightly frictionally held by one or more of the fingers 1145 after the operator's hand is removed and until the platen is rocked to press the papers against the pressure rollers 1132. The apertures in the arms 1157 (Fig. 3), through which the screws 1154 and 1156 pass, are somewhat vertically elongated to permit of accurate adjustment of the position of the upper edge of the line finder 1215 before those screws are tightened to clamp the arms 1157 and plate 1215 rigidly in position with respect to the member 1155.

The line finder plate 1215 detachably supports a form-heading holder 1216 (Figs. 7 and 8) having its longitudinal edges bent forwardly and toward each other to form channels to receive the edges of a form-heading paper strip. The member 1216 has secured in its back a plurality of headed studs 1217 insertable rearwardly in key-hole slots 1218 in the plate 1215. After the studs 1217 are inserted in the large right-hand ends of the slots 1218 the member 1216 is shifted leftwardly to place the necks of the studs 1217 in the narrow portions of the slots. When the member 1216 is in that position, a bluntly pointed stud 1219 projecting forwardly through an aperture in the line finder 1215 and secured in the free end of a spring 1220 secured at its other end to the back of the plate 1215, engages in an aperture 1221 in the back of the form-heading holder 1216 to releasably latch it in place. Whenever it is necessary to change from one kind of work involving one kind of forms to another kind of work requiring different forms, the form-heading holder may be removed by simply shifting it laterally to bring the studs 1217 into the large ends of the key-hole slots 1218 after which it may be withdrawn forwardly and replaced by another holder 1216 carrying the appropriate form headings.

When papers, such as a journal sheet and an overlying carbon sheet for the production of a running record of a series of posting operations, are to be inserted into the carriage, the operator will place the platen and platen frame in their front-feed positions. Also, the operator will move the lever 117 rearwardly to separate the lower pressure rolls 1155, the plate 1172 and the fingers 1145 from the platen 1057 as shown in Fig. 13. At that time the forward edge of the plate 1172 will rest on the upper surface of the plate 1172. The operator will also swing the front-feed paper chute assembly rearwardly about the studs 1151 from the position of Fig. 10 to the position of Fig. 11 so that a rearwardly directed cam projection 1222 of the right-hand arm 1153 acts on the roller 114 to swing the entire upper pressure roll assembly to the position of Fig. 11. Then the operator may insert the lower ends of the matching journal and carbon sheets downwardly between the front pressure rollers 1132 and the platen. The plates 1172 and 1178 guide the lower ends of the papers around the lower part of the platen. Then the operator may insert the upper ends of the papers between the platen and the upper rollers 1166, grasp the ends of the papers behind the platen, align the corners and pull the papers taut as shown in Fig. 15 to square them relative to the platen and then shift them lengthwise of the platen if necessary to align them between a pair of rear paper guides

1223 (Figs. 4 and 10) and thereafter return the front-feed paper chute assembly forwardly to lower the pressure rolls 1106 against the platen and return the lever 1121 forwardly to release the lower pressure rolls 1115 for return against the platen while still holding the ends of the papers with one hand. After the upper and lower pressure rolls 1106 and 1115 have been returned to active position, the operator may rotate the platen manually by means of the platen twirlers 1086, to bring the inserted journal sheet or the like to the desired line position to receive the imprint of the next entry to be printed. The carriage is then in condition for the insertion of front-feed forms, such as ledger and statement forms, after which the carriage may be closed.

Each of the rear paper guides 1223 (Figs. 4 and 10) comprises a plate extending across the upper side of the cross-support 1074 from the front to the rear thereof and bent around the rear and underneath the member 1074. The rear under-part of the member 1223 is secured to a T-block 1224 slidably in a T-way extending from end to end of the member 1074. A knurled thumb-screw 1225 threaded through the T-block 1224 permits of clamping the T-block in the T-way to hold the paper guides 1223 in any desired position of lateral adjustment. Each guide plate 1223 has on its lateral edge farthest removed from the other plate 1223 of the pair, an upturned flange 1226 to aid the operator in properly locating the side edges of the journal and carbon sheets or the like papers when placing them in the carriage.

Line-spacing means

The platen 1057 may be rotated manually by means of the twirlers 1086 while the machine is at rest and automatically, by variable line-space increments, through a pawl and ratchet means, the ratchet wheel of which is mounted on the platen shaft 1081 and normally drivingly connected thereto through a clutch which may be released manually temporarily to permit the platen to be placed in any position of fine rotary adjustment relative to the ratchet wheel so that a paper about the platen may be very accurately positioned to receive one or more lines of entries in the desired line-space relation to any rulings or previously made entries on the paper.

Immediately to the right of the spring clip 1084 (Fig. 9) a sleeve 1227 is rotatably supported on the platen shaft 1081. Rightward of the sleeve 1227, the platen shaft 1081 is of reduced diameter, forming an annular shoulder against which a spacing washer 1228 surrounding the platen shaft abuts. A hub 1229, freely rotatably mounted on the platen shaft 1081 and having its left-hand end spun into a ratchet wheel 1230, abuts against the right-hand face of the spacing washer 1228. The right-hand end portion of the hub 1229 is of reduced diameter to form, on the hub, an annular shoulder to abut the left-hand end of the hub portion of a clutch member 1231 which is secured on the hub 1229, against rotation relative thereto, by means of a set screw. A spring clip 1232, engaged in a circumferential groove in the platen shaft immediately to the right of the right-hand end of the hub 1229, holds the hub and the clutch member 1231 against movement longitudinally of the platen shaft.

The clutch member 1231 has a rightwardly extending annular flange formed with a finely

milled internal conical surface complementary to a finely milled external conical surface on a second clutch member 1233 loosely slidably surrounding the platen shaft. The two clutch members 1231 and 1233 are normally held in driving engagement by a spiral spring 1234 surrounding the platen shaft 1081 within a counterbore in the clutch member 1233 and held under compression by the left-hand end of the hub of the right-hand twirler 1086. The left-hand end of the hub of the right-hand twirler 1086 is spun into a disk 1235 having two opposite projecting teeth or lugs 1236 slidably engaging in rightwardly open slots formed in an annular flange 1237 extending rightwardly from the right-hand end of the clutch member 1233 so that the latter clutch member is always held against rotation relative to the platen, platen shaft and twirlers.

Automatic line-spacing rotation of the platen 1057 during machine operation is effected by driving the ratchet wheel 1230 by means of a power actuated line-spacing pawl 1238. As already described, the ratchet wheel 1230 is normally constantly coupled with the platen shaft 1081 and platen 1057 through the normally engaged clutch 1231, 1233 and the coupling 1236, 1237. The line-spacing pawl 1238 (Figs. 4 and 5) is pivotally mounted intermediate its ends on an eccentric bushing 1239 rotarily adjustably secured on a shouldered stud 1240 by a nut run onto the threaded reduced end of the stud. The stud 1240 is secured in the upper forward end of a curved arm 1241 secured on a shaft 1242 journaled at its ends in bushings secured in the carriage end plates 1069 and 1070. The shaft 1242 is held against endwise movement relative to the plates 1069 and 1070 by spring clips engaging in circumferential grooves formed in the shaft 1242 at the inward sides of the plates 1069 and 1070.

A tension spring 1243, anchored at its rear end to a stud 1244 secured in and projecting inwardly from the right-hand side plate 1069 and connected at its front end to the arm 1241, urges the latter and the shaft 1242 clockwise and normally maintains a projection 1245 of the arm 1241 engaged against the rear race rail of the member 1061. A tension spring 1246 is connected at its lower rear end to a shaft 1796 described hereinafter, and at its forward end to the rear arm of the pawl 1238 which is thereby urged clockwise to yieldingly hold its rearward arm engaged against the upper forward side of the right-hand bushing 1103.

A bail 1247 extending substantially from end to end of the carriage is secured to the flattened forward side of the shaft 1242 and may be swung rearwardly by power in selected machine operations through means described hereinafter to rock the shaft 1242 counterclockwise. As the shaft 1242 is rocked counterclockwise, the arm 1241 is likewise swung counterclockwise and thrusts the pawl 1238 forwardly. The spring 1246 maintains the rear arm of the pawl 1238 engaged against the bushing 1103 until the pointed upwardly turned forward end of the pawl engages the underside of a line-space-varying control shield 1248 extending rightwardly under the ratchet wheel 1230 from the lower arm of a two-armed lever 1249 secured to the right-hand end of the sleeve 1227. After the rear arm of the pawl 1238 leaves the bushing 1103, the nose of the pawl slides forwardly on the underside of the shield 1248 until the nose passes the forward end of the shield, where-

upon the spring 1246 rocks the pawl 1238 clockwise to engage its nose with the ratchet wheel 1230 so that, during the final portion of the rearward movement of the bail 1247 and forward movement of the pawl 1238, the pawl drives the ratchet 1230 and the platen clockwise to line-space the papers.

To prevent the platen from being rotated by its momentum beyond the position to which it is positively rotated by the pawl 1238, the latter has, below its driving nose, a downwardly extending cam projection 1259 which, at the forward end of the power stroke of the pawl, engages a stud 1251, adjustably secured in the plate 1069, so that the driving nose of the pawl 1238 is positively held between the teeth of the ratchet wheel 1230 and arrests rotation of the ratchet wheel and platen 1057 when the pawl reaches the end of its line-spacing stroke. The stud 1251 has a hexagonal flange on its rightward end which abuts the left face of the end plate 1069, and also has a threaded eccentric bore which receives a headed screw which passes through an eccentric bushing 1252 seated in an aperture in the plate 1069 and having a hexagonal flange on its right-hand end. After rotary adjustments of the bushing 1252 and the stud 1251 for proper contact of the stud 1251 with the cam projection 1259 at the forward end of the stroke of the pawl 1238, the screw may be tightened to secure the stud in adjusted position.

As the means by which the bail 1247 is swung rearwardly returns to normal, the springs 1243 and 1246 return the bail 1247, shaft 1242, arm 1241 and pawl 1238 to normal. The ratchet wheel 1230 and platen 1057, however, are yieldingly held in their advanced position by a detent comprising a yoke 1253 pivotally mounted on a stud 1254 secured in and projecting rightwardly from a rearward extension of the right-hand plate 1083. An upper forward arm on the right-hand side of the yoke 1253 carries a stud supporting a roller 1255 which is yieldingly pressed against the periphery of the ratchet wheel 1230 by a tension spring 1256 (Figs. 4 and 5) connected at its forward end to a lower forward arm of the yoke and at its rearward end to a stud 1257 (Fig. 4) secured in the right-hand plate 1083 forwardly of the shaft 1092.

The teeth of the ratchet wheel 1230 are formed with a spacing suited to the steps of variation in line-spacing desired to be obtained by adjustment of the control shield 1248, taking into account the relation between the diameter of the platen 1057 and the pitch diameter of the ratchet wheel 1230. The upper arm of the lever 1249 carries a rightwardly extending finger-piece by which the lever may be manually rocked to shift the shield 1248 circumferentially around the ratchet wheel 1230 to vary the point at which the ratchet wheel is engaged by the pawl 1238 in the forward stroke of the latter and thereby vary the number of tooth-spaces through which the ratchet is driven by the pawl in each of its forward strokes.

The edge of the lever 1249 upwardly and rearwardly of the platen shaft 1081 is formed with a series of notches extending arcuately about the axis of the platen shaft 1081 and cooperating with a stud 1258 projecting rightwardly from and carried by the upper forward arm of a yoke 1259 pivotally supported on the stud 1254 between the sides of the yoke 1253. A lower forward arm of the yoke 1259 is connected with the forward end

of a tension spring 1260 anchored at its rear end to the stud 1257 so that the stud 1258 yieldingly holds the lever 1249 and shield 1248 in any selected one of a series of positions of adjustment. The notches in the edge of the lever 1249 have the same angular spacing as the teeth of the ratchet 1230 and are so located relative to the forward edge of the shield 1248 and the position of the stud 1258 that in each successive position of adjustment of the upper arm of the lever 1249 from the rear forwardly, the extent of rotation of the ratchet 1230 by the pawl 1238 permitted by the shield 1248 is lengthened by one tooth-space.

The spring pressed detent roller 1255, by yieldingly holding the ratchet wheel 1230 in one or another of the positions in which the roller 1255 presses upon two adjacent teeth of the ratchet wheel and by automatically rotating the ratchet wheel and platen 1057 to such a position from any intermediate position whenever it is not otherwise held in such an intermediate position, aids in securing uniformity of line-spacing of the forms about the platen even when the operator manually line-spaces the forms by means of the twirlers 1086. There are times, however, when adjustment of the forms by amounts less than the amount corresponding to the spacing of the teeth of the ratchet wheel 1230 is desirable, as for example, when either a new or a partially filled journal sheet is inserted in the carriage in the manner previously described. It will be remembered that, after matching the upper and lower corners of the journal sheet at each side thereof, pulling the sheet taut and sliding it laterally to the correct position, and returning the pressure rollers 1108 and 1115 into active position, the operator manually rotates the platen by means of the twirlers 1086, or one of them, to adjust the journal sheet to the proper line-space position. In order to permit accurate positioning of the journal sheet in that manner always to within a small fraction of one of the line-space increments determined by the teeth of the ratchet wheel, it is necessary to uncouple the ratchet wheel 1230 from the platen. To do that, the operator, preferably after returning the platen to printing position where the printing line may be determined by reference to the upper edge of the shield 1075, manually presses the right-end flange of the clutch member 1233 toward the right-hand twirler 1086 thereby retracting the clutch member 1233 from engagement with the clutch member 1231 against the tension of the spring 1234, the slots 1237 being of sufficient depth to permit such separation of the two clutch members. Then the platen 1057 may be rotated manually to any desired extent by either of the twirlers 1086 while the ratchet wheel 1230 is held stationary by the detent roller 1255, the clutch member 1233 rotating relative to the clutch member 1231 and with the platen and twirlers. When the operator releases the clutch member 1233, the clutch is re-engaged by the spring 1234 and the platen is yieldingly held in its rotarily adjusted position.

PAPER CARRIAGE OPERATING MECHANISM

Sub-frame (Gear box)

The mechanism for operating the paper carriage and various portions of the carriage, that is the motor driven mechanism by which the carriage is moved in both the tabulating and return directions and that by which the bails 1096 and 1247 are rocked to open and close the carriage

and to rotate the platen for line-spacing the papers thereon, is supported mainly by and largely within a box-like sub-frame which, for convenience, will hereinafter be referred to as the "gear box."

The gear box comprises two spaced side plates 1261 and 1262 (Figs. 23 and 24), each of which has a front upward projection 1263 (Fig. 23) having a lug bent laterally outwardly from its upper front edge for attachment to the rear face of the frame cross member 42 as by means of a headed screw passing through the lug and threaded into the member 42. Each of the side plates 1261 and 1262 also has a rear upward projection 1264, the upper end of which is bent laterally outwardly for securement to the underside of the rear carriage race rail 44 as by means of headed screws passing through the laterally bent portions of such projections and threaded into the rail 44.

A bottom plate 1265 (Fig. 25) has on each of its lateral edges, two upturned lugs 1266 secured against the inner face of the adjacent side plate 1261 or 1262 near the bottom edge of the latter, as by means of headed screws passing through the side plate and the lugs and having nuts threaded on their ends. The head of the screw securing the left rear lug of the bottom plate to the left side plate 1262 is constituted by a post 1267.

A top plate 1268 (Fig. 23) has, on each of its side edges, front and rear bent-down lugs 1269 for securement to the inner face of the adjacent side plate 1261 or 1262 as by means of screws passing through the lugs and side plate and having nuts threaded on their ends, the heads of the three screws other than the left front one being posts 1270, 1271 and 1272 serving to support parts described hereinafter. A rear plate 1273 has on each of its side edges upper and lower forwardly bent lugs 1274 secured to the inner face of the adjacent side plate 1261 or 1262 as by headed screws passing inwardly through the side plate and lugs and having nuts threaded on their inner ends, the head of the screw in the upper left lug 1274 being a post 1275. The gear box, having no front plate, is open at its forward end.

As disclosed in the above-mentioned copending application, the gear box contains carriage tabulating and return drive means powered by the machine cycling motor independently of the machine cycling clutch through bevel gears 1278 and 1280 (Fig. 23), shaft 1281, a friction overload slip clutch 1285, a shaft 1291 (Fig. 25) and bevel gears 1299 and 1300. The tabulating and return drive means comprises a gear 1306 which meshes with the gear 1301 and is rotatably mounted on a shaft 1307 journalled in bushings (not shown herein) in the top and bottom plates 1268 and 1265 of the gear box. The gear 1306 is driven clockwise at all times when the motor is running, regardless of whether the machine is or is not being driven through a cycle of operation.

Carriage opening and closing drive

A gear 1607 (Fig. 24) secured on the lower end of the hub of the gear 1306, meshes with an idler gear 1608 secured on a hub rotatable on a headed stud 1609 secured in the gear box bottom plate 1265. The gear 1608 meshes also with a gear 1610 which is thereby driven clockwise whenever the motor runs. The gear 1610 (Fig. 29) is secured upon the lower end of the hub of a clutch member 1611 (also Fig. 31) rotatable on a shaft 1612 which is rotatable in bushings in the top and bot-

tom plates 1268 and 1265. A second clutch member 1615 (Figs. 29 and 31) with a notched disk 1616 secured on its upper end is rigidly secured upon the shaft 1612. The shaft 1612, clutch members 1611 and 1615 and disk 1616 are held against vertical movement by engagement of the hub of the lower clutch member 1611 with the bushing in the bottom plate 1265 and engagement of the disk 1616 with the bushing in the top plate 1268.

The clutch 1611, 1615 is constructed as shown in Figs. 31, 32 and 33. Between the outer and inner circumferential walls of the lower clutch member 1611 (Fig. 32) is a space shaped as though formed by drilling from the upper surface a number of cylindrical bores of uniform small diameter d' , the axes a' of which are spaced apart a uniform distance e' substantially less than the diameter d' of the bores and lie in a circular cylinder, the diameter c' of which may be equal to or slightly greater than the sum of the radii r' and s' of the inner and outer cylindrical surfaces, respectively, of the body of the member 1611. The radius s' , of course, is substantially greater than the sum of r' plus d' .

The upper cylindrical portion of a clutch dog 1617 is rotatably fitted in a bore formed in the upper clutch member 1615 with its axis displaced from the axis of the shaft 1612 the same distance as the axes a' , above mentioned, are displaced from the axis of the shaft 1612. The lower end of the clutch dog 1617 is shaped as though formed from a cylinder having a free-running fit in any of the above-mentioned bores of diameter d' but cut away concavely on one side and convexly on the opposite side so that, in the dot-dash line position of Figs. 31 and 32, it has a driving engagement with the clutch member 1611, but when rotated counterclockwise through a small angle to the full line position of Fig. 32, the convex and concave sides of the lower end of the dog 1617 are approximately concentric with the shaft 1612 and out of the paths of the cusps of the lower clutch member 1611 so that the latter will be permitted to rotate freely on the shaft 1612 relative to the upper clutch member 1615 and the dog 1617. The upper clutch member 1615 is formed with a horizontal slot entering it from one side and containing a semi-annular clip 1618 hooked on a pin 1619 secured in the clutch dog 1617. A tension spring 1620, connected at one end to a grooved stud penetrating into the slot in the member 1615, is connected at its other end to a lug on the clip 1618 and urges the clutch dog 1617 to the position of Fig. 31 where it is stopped by engagement of an arm 1621 rigid on the dog 1617 against an edge of a notch formed in the member 1615 to accommodate angular movement of the arm 1621 as the dog rotates between the full line and dot-dash line positions of Fig. 32.

A slide 1622 (Fig. 33) having a somewhat C-shaped portion surrounding the left half of the clutch member 1615, also has, in its front and rear portions, forwardly and rearwardly elongated slots receiving the shouldered lower ends of posts 1623 and 1624 secured at their upper ends in the gear box top plate 1268, the slide being retained on the ends of the posts as by headed screws. A C-shaped double pawl 1625 on the lower side of the slide 1622 is pivoted on a headed stud 1626 secured in the slide and has, at its ends, lugs 1627 and 1628 turned up and extending through openings in the slide into the path of the arm 1621. The lugs 1627 and 1628 of the pawl 1625 are so spaced relative to

each other and to the stud 1626 that whenever either of the lugs 1627 and 1628 is outside of the path of the end of the arm 1621, the other lug 1627 or 1628 is in the path of the arm 1621. A tension spring 1629 on the lower side of the pawl 1625 is connected at its right-hand end to a stud secured in the slide 1622 and its left end to a stud secured in the forward portion of the pawl 1625 so as to urge the pawl counterclockwise, i. e., counter to the direction of rotation of the clutch.

When the clutch dog 1617 is in the position indicated in dot-dash outline in Fig. 32, where it is held in engagement with two cusps of the clutch member 1611 by the spring 1620, the lower clutch member 1611, being driven clockwise by the motor, will be driving the dog 1617, upper clutch member 1615, shaft 1612 and disk 1616 clockwise so that, shortly, the arm 1621 will be brought into engagement with the lug 1627 of the pawl 1625. Because of the driving engagement of the clutch member 1611 with the dog 1617, the arm 1621 rocks the pawl 1625 against the tension of the spring 1627 until the pawl is stopped by engagement of the end of a slot therein against a stud 1630 secured in the slide 1622 extending into the slot. The outer end of the arm 1621 is thereby also stopped so that continuing rotation of the upper clutch member 1615 causes the dog 1617 to be rotated counterclockwise to disengage it from the lower clutch member 1611 whereupon the spring 1629 is able to overcome the spring 1620 and restore the pawl 1625 counterclockwise so as to rotate the dog 1617 further counterclockwise to the full line position of Fig. 32 where ample clearance is provided between the corners of the lower end portion of the dog and the cusps of the lower clutch member 1611 which continues to be driven by the motor.

A tension spring 1631 (Fig. 29) is secured at its forward end to a stud secured in the top plate 1298 of the gear box and at its rear end to the left arm of a lever 1632 pivoted intermediate its ends on a stud 1633 secured in the plate 1268. The rightward arm of the lever 1632 carries a headed stud upon which is a roller 1634 which, whenever the clutch dog 1617 is held in disconnected position by an end 1627 or 1628 of the pawl 1625, is pressed into one or the other of two V-notches in the disk by the spring 1631 and holds the disk, the clutch member 1615 and the dog 1617 from being reversely rotated by the spring 1620. The clutch dog 1617 is thereby held in disconnected position and chattering is prevented.

It will be apparent that, while the motor is running, each time the control slide 1622 is shifted from its rearward position to its forward position or reversely to release the arm 1621 from the lug 1627 or 1628 previously holding it, the clutch 1611, 1615 will be coupled to drive the shaft 1612 through one-half of a revolution and then uncoupled as the arm 1621 is stopped by the other of the lugs 1627 and 1628.

A crank arm 1635 (Fig. 29) is secured on the upper end of the shaft 1612 so that it is directed at a small angle in advance of the axis of the clutch dog 1617. Rotatably fitted into the end of the crank arm 1635 is a stud secured in a connecting link 1636 pivoted on a stud 1637 secured on a slide 1638, the link being retained on the stud 1637 as by a headed screw. The slide 1638 has three forwardly and rearwardly elongated slots which receive the reduced ends of three

stud 1639 secured in the plate 1268, the slide being retained on the studs 1639 as by means of headed screws. Rollers 1640 are mounted above the slide 1638 on two rotatably adjustable eccentric studs secured in forwardly and rearwardly spaced relation on the forward portion of the slide 1638, the spacing between the rollers being just sufficient to freely accommodate the previously-described carriage-opening bail 1096 between the rollers. As previously explained, the carriage is closed by rearward movement of the bail 1096 and opened by forward movement of the bail.

While the motor is running, movement of the control slide 1622 from its forward to its rearward position will cause the clutch 1611, 1615 to drive the slide 1638 and bail 1096 forward to open the carriage and return of the control slide 1622 to its forward position will cause the clutch to drive the slide 1638 and bail 1096 rearward to close the carriage.

Manual control of carriage opening and closing

The carriage opening and closing key 1641 (Figs. 2 and 25) comprises a lever 1642 secured upon a hub pinned on the right-hand end of a shaft 1498 rotatably mounted in the side frame plate 21 and in a bracket 659 secured to the frame cross member 42. An arm 1643 is secured to a hub also pinned on the shaft 1498 near the left end of the latter. A tension spring 1544 connected at its rear end to the arm 1643 and at its forward end to a plate 1515 secured to the frame cross member 41 urges the arm 1643 clockwise against a stud 1516 secured in and extending rightwardly from a downward branch of the bracket 659. A stud 1645 is secured in the lower end of the arm 1643 in front of the forward end of a link 1646 (Fig. 27) pivotally and slidably guided on a grooved stud 1490 which is secured in and projects rightwardly from the right-hand side plate 1261 and passes through a forwardly and rearwardly elongated slot in the link 1646. A tension spring 1647 connected at its forward end to a stud 1494 secured in the plate 1261 and at its rearward end to a downward projection of the link 1646 urges the link forwardly and its forward portion upwardly into the top of a slot in a comb guide bracket 1491 (Fig. 28) secured to the right-hand side of the plate 1261.

A pawl 1648 (Fig. 27) is pivoted at its rearward end on a headed stud 1649 secured in the link 1646 and, intermediate its ends, carries a stud 1650 engaging in an upwardly and downwardly elongated slot in the link 1646 whereby swinging of the pawl 1648 relative to the link 1646 is limited. The forward end of the pawl 1648 is urged downward by a light tension spring 1651 connected at its forward end to a downward projection of the pawl and at its rear end to a downward projection of the link 1646. A somewhat T-shaped upward projection 1652 of the pawl 1648 normally, that is, when the pawl is in its lower position, has its rearward arm positioned immediately in front of a rightwardly bent upward arm of a bell crank 1653 (Fig. 29) secured on a hub which bears against the right side of the plate 1261 and is pinned on a short shaft 1654 which passes through the plate 1261.

A two-armed member 1655 is secured on a hub which bears against the left side of the plate 1261 and is also pinned on the shaft 1654. An upper arm of the member 1655 has an upwardly open slot receiving a stud 1656 secured in a rightward extension of the control slide 1622. A forward

arm of the member 1655 carries a stud 1657 which is engaged by the double V-notched rear edge of a detent arm 1658 pivoted at its upper end on a headed stud 1659 secured in the plate 1261 and urged counterclockwise by a tension spring 1680 connected at its forward end to the detent arm and at its rear end to a stud secured in the plate 1261. The forward end of the forward arm of the member 1655 is spear-shaped and cooperates with a stud 1691 secured in the lower arm of a two-armed member 1662 secured on a shaft 1663 journaled in the gear box side plates 1261 and 1262. The member 1662 and shaft 1663 are urged counterclockwise by a tension spring 1664 connected at its rear end to the upper arm of the member 1662 and at its forward end (Fig. 36) to a stud 1665 secured in the plate 1261.

A lever 1666 (Figs. 29 and 30), rigidly secured on the left end of the shaft 1663 immediately to the left of the plate 1262, has a projection 1667 extending upwardly above the shaft 1663 and normally yieldingly held, by the spring 1664, engaged against the rear of a stud 1668 (Figs. 35 and 36) secured in and extending leftwardly from the plate 1262. The lever 1666 also carries a stud 1669 projecting leftwardly immediately above the rightwardly bent lug 1373 of a switch-operating yoke 154 which, when rocked clockwise, operates the arm 159 to close the switch of the machine drive motor as disclosed in the above-mentioned parent application. Thus, clockwise movement of the shaft 1663 and lever 1666 against the tension of the spring 1664 causes the motor switch to be closed.

On the lower rear end of the lever 1666 is a lug 1670 (Fig. 30) which extends rightwardly through an opening in the plate 1262 and cooperates with the shouldered lower end of a latch lever 1671 which is located on the right side of the plate 1262, is pivoted on a stud 1672 secured in the plate 1262, and is urged counterclockwise by a tension spring 1673 connected at its forward end to a lug on the latch lever and anchored at its rearward end on the shaft 1654. When the lever 1666 is moved to close the motor switch, the lug 1670 is lowered below the shoulder on the latch lever 1671 which is thereupon rocked counterclockwise by the spring 1673 to latch the lever 1666 in switch-closing position.

A slide 1674 on the underside of the plate 1268 has forwardly and rearwardly elongated slots receiving headed stud secured in the plate 1268. The slide 1674 carries a stud 1675 projecting downwardly immediately behind the left end of the arm 1632 and has two projections 1676 and 1677 extending leftward in front of the upper arm of the latch lever 1671 and the projection 1667 on the forward end of the lever 1666, respectively, and in such relation to the later two elements that, when the slide 1674 is moved rearwardly, the projection 1676 engages the latch lever 1671 and moves it away from the lug 1670 before the projection 1677 rocks the lever 1666 far enough to lower the lug 1670 below the latching shoulder on the lever 1671.

The forward arm of the bell crank 1653 (Fig. 29) has a stud and slot connection with the rearward arm of a second bell crank 1678 pivotally supported on the stud 1588, and spaced from the plate 1261 by a spacing collar. The rocking of either of the two bell cranks 1653 and 1678 causes the other of them to be rocked in the opposite direction. A yoke 1679, pivotally mounted on the stud 1588 between the bell crank 1678 and the lever 1587 (Fig. 27), has at its right end a

rearwardly and upwardly inclined arm 1680 (Fig. 29) which is positioned under a stud 1681 secured in and extending leftwardly from the pawl 1648. A tension spring 1682, strong enough to overcome the spring 1651, is connected between the rightwardly bent upper arm of the bell crank 1678 and a stud secured in the arm 1680 and urges a leftwardly turned projection 1683 of the arm 1680 against the rearward edge of the upper arm of the bell crank 1678.

The parts are so proportioned and arranged that in their normal positions (Fig. 29), the control slide 1622 is in its forward position with the paper carriage closed, and the arm 1680 is held in its lower position by the bell crank 1678 and permits the pawl 1648 to occupy its lower position with the rear arm of the T-shaped projection 1652 aligned with and immediately in front of the rightwardly bent upper arm of the bell crank 1653. With the parts so positioned, depression of the key 1641 swings the arm 1643 and stud 1645 to move the link 1646 and pawl 1648 rearwardly so that projection 1652 rocks the bell crank 1653 and member 1655 clockwise to move the control slide 1622 rearwardly to release the arm 1621 and permit the clutch dog 1617 to be rotated to coupling position by its spring 1620. At the same time, the forward arm of the member 1655 carries the stud 1657 from the lower to the upper of the two notches in the detent 1658 and the forward end of said arm, as it passes the stud 1661, cams the latter forward momentarily to rock the shaft 1663 and lever 1666 against the tension of the spring 1664 far enough to lower the lug 1670 below the shoulder of the latch lever 1671 which then holds the lever 1666 in such position that the stud 1669 holds the switch-operating yoke 154 in switch-closing position.

As the bell crank 1653 is rocked clockwise by the pawl 1648 during depression of the key 1641, the bell crank 1678 is rocked counterclockwise and stretches the spring 1682 while the rightwardly bent upper arm of the bell crank 1653 is engaged by and prevents upward movement of the projection 1652, and, consequently, prevents the yoke 1679 from following the bell crank 1678. When the operator permits the key 1641 to be returned to normal by the spring 1644, the link 1646 and pawl 1648 are also returned forwardly by the spring 1647 and, as the projection 1652 is disengaged from the bell crank 1653, the spring 1682 then rocks the arm 1680 to engage the lug 1683 against the bell crank 1678 and rocks the pawl 1648 clockwise to lift the rearward arm of the projection 1652 above the rightwardly bent arm of the bell crank 1653. An upwardly and rearwardly directed hook 1684 on the forward end of the pawl 1648 is simultaneously positioned in front of the rightwardly bent portion of the upper arm of the bell crank 1678.

As the upper clutch member 1615, the disk 1616, shaft 1612 and crank 1635 are driven by the motor, the disk 1616 cams the roller 1634 forward, rocking the lever 1632 clockwise and moving the stud 1675 and slide 1674 rearward to disengage the latch 1671 from the lever 1666. However, the projection 1677 then holds the projection 1667, lever 1666, stud 1669 and switch-operating yoke 154 in switch-closing position. As the clutch opens the paper carriage, completes a half-revolution, and is uncoupled, the roller 1634 enters the other notch in the disk 1616 as the spring 1631 rocks the lever 1632 to permit the slide 1674, lever 1666 and shaft 1663 to be

returned to normal by the spring 1664 and to permit the motor switch to be opened by its spring 166.

It will have been noted that the pawl 1648 has been positioned so that when it is moved rearwardly by a second depression of the key 1641, it rocks the bell crank 1678 and yoke 1679 clockwise and the bell crank 1653 and member 1655 counterclockwise which moves the clutch control slide 1622 forwardly to couple the clutch for another half-revolution and closes the motor switch so that the carriage will be closed. As the key 1641 again returns to normal, and the hook 1684 disengages from the bell crank 1678, the pawl 1648 drops again to its lower position where, upon a further depression of the key 1641, it will cause the carriage to be opened. Thus, if the carriage is in closed condition, depression of the key 1641 causes it to be opened by power, whereas when the carriage is open, depression of the same key 1641 causes the carriage to be closed by power.

Automatic closing of carriage at beginning of machine cycle

As described above, each time the clutch control slide 1622 is moved rearward to cause the carriage to be opened, the bell crank 1672 rocks counterclockwise. A link 1685 (Fig. 29) has a forwardly and rearwardly elongated slot which receives a reduced end of a shouldered stud 1686 secured in the plate 1261, the link being retained on the stud by means of a headed screw threaded into the stud. At its rear end the link 1685 is pivotally connected, as by a headed stud, to the upper arm of the bell crank 1678 whereby, each time the carriage is opened, the link 1686 is moved forwardly to position its forward end immediately in front of a stud 1687 secured in the lower end of an arm 1688 having, at its upper end, a yoke portion pivoted on the shaft 1498 just to the right of the bracket 659. The arm 1688 is urged clockwise against the stud 1516 by a tension spring 1689 connected between said arm and the plate 1515. The arm 1688 has a forwardly directed knee-shaped cam projection 1690 in the path of a stud 1691 projecting leftwardly from and secured in a gear 1503 secured on the main shaft 126 of the machine which, as disclosed in the above-mentioned parent application, is rotated clockwise through one revolution in each machine cycle. The cam projection 1690 is located in such a position that, at the beginning of each cycle of operation of the machine, the stud 1691 cams the arm 1688 and stud 1687 rearwardly so that, if the paper carriage is open as a cycle of operation of the machine is initiated, the stud 1687 will push the link 1685 to its rearward position and rock the bell crank 1678 clockwise and the bell crank 1653 and member 1655 counterclockwise to move the clutch control slide 1622 forwardly to cause the carriage to be closed before the printing hammers are fired in the cycle of operation of the machine.

Line spacing power drive

The idler gear 1608 (Fig. 24) also meshes with a gear 1692 secured on the lower end of a clutch member 1693 (Fig. 36) bearing on the gear box bottom plate 1265 and normally freely rotatable on a shaft 1694 journalled in bushings 1695 and 1696 in the plates 1265 and 1268, respectively. Above the clutch member 1693, a clutch member 1697 and a disk 1698 are rigidly secured to the shaft 1694. The clutch comprising the members

1693 and 1697 is in all respects like the clutch of Figs. 31, 32 and 33, but the control means (Figs. 34 and 36) are arranged to cause the clutch 1693, 1697 to drive the shaft 1694 through a full revolution each time the clutch is coupled, and the disk 1698 has but a single notch therein.

A lever 1699 (Fig. 36) pivoted on the stud 1633 between the lever 1632 and the plate 1268 has a rearwardly extending arm which carries a roller stud 1700 pressed against the edge of the disk 1698 by a tension spring 1701 connected between the rear end of the lever 1699 and a stud secured in and projecting downwardly from the plate 1268. The roller 1700 normally is engaged in the single notch in the disk 1698 to yieldingly hold the disk, the clutch member 1697 and shaft 1694 against rotation while the clutch dog 1702 (Fig. 34) is held in uncoupled position by engagement of its arm 1703 with an upstanding lug of a pawl 1704. While the upper clutch member 1697 and shaft 1694 are in that position, a roller stud 1705 (Fig. 37), which is secured on a cam disk 1706 secured, as by spinning, on the upper end of the shaft 1694 above the plate 1268 and extends upwardly immediately in front of the previously described line-spacing bail 1247, permits the latter bail to occupy its normal forward position to which, as previously described, it is urged by

The pawl 1704 (Figs. 34 and 36) is pivoted on a stud 1707 secured in a leftwardly turned flange of an arm 1708 rigid on a hub pinned on a shaft 1709 journalled in the plates 1261 and 1262. A tension spring 1710 (Fig. 34) connected between the arm 1708 and a stud secured in the pawl 1704 normally overcomes the tension of a clutch dog spring like the previously-described spring 1620 of Fig. 31 and holds the pawl 1704 at the clockwise limit of the movement permitted by a stud 1711 which is secured in the flange of the arm 1708 and projects into an aperture in the pawl.

An arm 1712 (Fig. 36) is secured on a hub pinned on the shaft 1709 a little to the left of the arm 1662 and has a lug 1713 extending rightwardly in front of a stud 1714 secured in the upper arm of the lever 1632. A tension spring 1715 is connected at its rearward end to the arm 1712 and is anchored at its forward end on the stud 1665 and normally yieldingly holds the shaft 1709 and arms 1708 and 1712 in the normal positions of Fig. 36 where the arm 1712 is stopped by a stud 1716 secured in and extending leftwardly from the plate 1261. An arm 1717 secured on and extending upwardly from the rightward end of the shaft 1709 carries a stud 1718 positioned in front of an upward projection of a link 1719 which is pivotally and slidably mounted similarly to the links 1523 and 1646 and between them on the stud 1490 (Fig. 28) and similarly guided in the comb guide bracket 1491. A tension spring 1720 connected between the stud 1494 and a downward projection of the link 1719 urges the link forwardly and upwardly to a position where its front end is above and slightly to the rear of a stud 1499 carried in the lower end of an arm 1495 having at its upper end (Fig. 25) a yoke portion rotatable on a sleeve 1497 which, in turn, is rotatably supported on the shaft 1493. A tension spring 1496 connected at its front end to the plate 1515 and at its rear end to the arm 1495 normally yieldingly holds the latter forwardly against the stud 1516. The lower portion of the arm 1495 also has a cam projection 1500 extending forwardly into the path of a stud 1501 secured in an arm 1502 secured on the hub of the gear 1503 whereby the arm 1495 is swung

rearward after printing in each cycle of operation of the machine.

Whenever the link 1719 is moved rearwardly, it, through the stud 1718 and arm 1717 (Fig. 36), rocks the shaft 1709 clockwise so that the arm 1712 acts on the stud 1714 to rock the arm 1652, the shaft 1663 and the lever 1666 clockwise to close the motor switch, and cause the lever 1666 to be held by the latch 1671 as previously described. At the same time, the arm 1708 and pawl 1704 are rocked clockwise to release the clutch control arm 1703 and permit the clutch 1693, 1697 to become coupled whereby the shaft 1694, disk 1698 and cam 1706 are rotated. As the roller 1700 is forced out of the notch in the disk 1698, the lever 1699 is rocked clockwise so that its leftward arm acts on the stud 1675 to move the slide 1674 rearwardly to trip the latch 1671 but hold the lever 1666 in switch-closing position until, at the completion of the revolution of the clutch, the roller 1700 is again pulled into the notch in the disk 1698 by the spring 1701.

As the shaft 1694 is rotated, the roller 1700 first forces the line-space bail 1247 rearwardly to rotate the platen one or more line spaces as previously described, and then permits the bail 1247 to return forwardly to normal position. As the revolution of the clutch 1693, 1697 and shaft 1694 is completed, the shaft 1709 and slide 1719 having meanwhile been returned to normal, as also will be described later, the pawl 1704 is engaged by the arm 1703 and the clutch is uncoupled in the same manner as above explained with reference to the clutch 1611, 1615.

Manual control of line-spacing

Line-spacing of the platen normally is effected in machine cycles initiated by manual depression of either the "Vertical" bar 293 or the "Return" bar 294 (Fig. 1).

Depression of either the "Vertical" bar 293 or the "Return" bar 294, as described in the above-mentioned parent application, rocks counterclockwise a yoke 1727 (Fig. 30) having a forwardly extending left side arm carrying a stud 1729 which overlies the link 1719. Upon such counterclockwise rocking of the yoke 1727, the stud 1729 depresses the forward end of the link 1719 into the path of the stud 1499 so that after operation of the printing mechanism, the stud 1499 moves the link 1719 rearwardly momentarily to cause the above-described power-driven line-spacing mechanism to line space the platen.

The line-spacing mechanism is also controlled automatically as disclosed in the above-mentioned copending application to effect line-spacing of the platen also in other operations of the machine and to suppress line-spacing in certain operations initiated by depression of the "Return" bar 294 or while that bar is in depressed position, and in all machine operations performed while the automatic function controls are disabled.

Automatic controls

The machine is also provided with automatic function control means which, as disclosed in the above-mentioned copending application, includes means for automatically controlling the above-described links 1646 and 1719 to cause opening of the carriage to be effected and line-spacing of the platen to be effected or suppressed in selected cycles of operation of the machine in accordance with the columnar positioning of the paper carriage.

INTERLOCKS

Preventing cycling of machine while carriage opening and closing key is depressed and preventing depression of that key during machine cycles

The carriage opening and closing key-stem 1641 has a forward projection 2175 and the machine has a bail rod 215 (Fig. 27) which normally is positioned just forwardly of and just below the lower front corner of the projection 2175. Depression of the carriage opening and closing key places the projection 2175 immediately behind the bail rod 215. As disclosed in detail in the above-mentioned parent application, a cycle of operation of the machine cannot be initiated unless and until the bail rod 215 has moved rearwardly under the projection 2175 where it remains until well after operation of the printing mechanism in the course of the machine cycle. Thus a cycle of operation of the machine cannot be initiated unless the carriage opening and closing key-stem is in its normal undepressed position and said key-stem cannot be depressed during a machine cycle until well after operation of the printing mechanism.

Preventing initiation of machine cycle during opening of the paper carriage

If a machine cycle is initiated while the paper carriage is fully opened, the carriage is automatically closed during the early part of the machine cycle and such closing is completed prior to the time at which printing occurs, as previously explained. However, a machine cycle cannot be started while the carriage is opening. Even though the operator may depress a "live" key or motor bar while the carriage is opening, the starting of the machine cycle is delayed until the carriage is fully opened and ready for automatic closing at the commencement of the machine cycle.

As previously explained, movement of the carriage opening and closing clutch control slide 1622 (Figs. 29 and 35) from its forward to its rearward position causes engagement of the clutch for a half-revolution to open the carriage and a return of the slide 1622 to its forward position causes engagement of the clutch for another half-revolution to close the carriage. While the clutch is disengaged and the carriage is closed, the slide 1622 is in its forward position where a forwardly facing shoulder 2176 thereon (Fig. 35) engages an upstanding lug 2177 on the rightward end of a yoke 2178 which is pivotally supported on the shaft 1709. The yoke 2178 is urged clockwise by a tension spring 2179 anchored at its lower end in an eye in the gear box bottom plate 1265 and connected at its upper end to a rearward left side arm of the yoke 2178. The latter arm carries a stud 2180 which projects leftward through an aperture in the gear box left side plate 1262 and engages in the forked end of a rearward arm on the right-hand side of a yoke 2181 which is pivotally mounted on a stud 2182 secured in the right-hand side portion of the bracket 148. An upward arm on the left side of the yoke 2181 has on its rear edge a shoulder 2183 adapted to block a lug 196 of the machine cycling control arm 192 against moving downward far enough as disclosed in the above-mentioned copending application to cause the main drive clutch to be engaged to cycle the machine.

While the control slide 1622 for the carriage opening and closing clutch is in its forward position, its shoulder 2176 engaging the lug 2177

holds the yoke 2178 in a counterclockwise position in which the stud 2180 holds the yoke 2181 in a counterclockwise position such that the shoulder 2183 is forward of and does not interfere with downward movement of the lug 196 to initiate a machine cycle. However, when the slide 1622 is moved rearwardly to cause the carriage to be opened, the spring 2179 rocks the yokes 2178 and 2181 clockwise to move the shoulder 2183 under the lug 196 so that a machine cycle cannot be initiated while the carriage is opening.

As the driven portion 1615 of the clutch and the shaft 1612 nearly complete a half-revolution to open the carriage, a stud 2184, secured in the disk 1616 which rotates with the shaft 1612, engages the rightward cam end of a lever 2185 which is horizontally swingably mounted on the stud 1633 between the lever 1699 and the plate 1268 and is urged counterclockwise by a tension spring 2186 connected at its rear end to a leftward arm of the lever 2185 and at its forward end of a stud secured in the underside of the plate 1268. In the final portion of the carriage-opening half-revolution of the shaft 1612, the stud 2184 cams the lever 2185 clockwise so that the down-turned end of a forward projection 2187 of the lever 2185 acts on the lug 2177 and rocks the yokes 2178 and 2181 counterclockwise to move the shoulder 2183 forwardly clear of the lug 196 to permit the latter to be moved downward to initiate a machine cycle in the initial portion of which the stud 1687 (Fig. 29) will push the slide 1685 rearwardly to cause the carriage to be closed before printing occurs.

Preventing initiation of machine cycle while open paper carriage is not properly conditioned for closing.

While the front-feed paper chute and line finder assembly remains in the upper rearward position (Fig. 11) to which it is moved for facilitating insertion of a journal sheet, initiation of a machine cycle is prevented.

The right-hand one of the two arms 1166 has on its lower end portion a forward projection carrying on its outward side a roller stud 2211 under the lower edge of a generally forwardly and upwardly extending cam arm 2212 of a bell crank 2212, 2213, having a hub rotatably mounted on the stud 1175 adjacent the carriage frame side plate 1669. The second arm 2213 of the bell crank 2212, 2213 extends downwardly and forwardly under and behind a stud 2214 projecting from the right side of the arm 1241. The lower edge of the cam arm 2212 is so shaped that during the initial movement of the arms 1166 and 1153 clockwise as the front-feed paper chute and line finder assembly is moved upwardly and rearwardly from its normal position toward the journal sheet inserting position, the roller 2211 cams the bell crank 2212, 2213 clockwise so that the arm 2213, acting on the stud 2214 rocks the arm 1241, the shaft 1242 and line-spacing bail 1247 counterclockwise from their normal positions. The remainder of the clockwise movement of the arms 1166 is without effect on the positions of the bell crank 2212, 2213, arm 1241 and bail 1247.

A roller stud 2215 (Figs. 23 and 37) is mounted on the upper side of a slide 2216 which has a forked rearward end slidably embracing the upper end of a stud 2192 which is secured in the plate 1268. The slide 2216 is urged rearwardly by a tension spring 2217 which is connected at its forward end to a leftward ear on the slide and

5 at its rearward end to a stud 2194 secured in the plate 1268. The spring 2217 yieldingly holds the roller stud 2215 against the forward side of the bail 1247 while the latter is in its normal position. The forward end portion of the slide 2216 is pivotally connected to the rightward arm of a lever 2218 which is pivoted on the upper end of a stud 2189 secured in the plate 1268 and has a downwardly turned left end with a forward projection 2219. When the line-spacing bail 1247 is swung rearwardly, as above explained, by movement of the front-feed paper chute and line finder assembly from the position of Fig. 10 toward the position of Fig. 11, the spring 2217 pulls the slide 2216 and roller 2215 rearwardly a short distance and swings the lever 2218 counterclockwise to move the projection 2219 under the lug 196 so that the latter cannot move downward to initiate a machine cycle until the front-feed paper chute and line finder assembly is returned to its normal position to permit the spring 2143 to return the line-spacing bail 1247, slide 2216 and lever 2218 to normal.

25 In a line-spacing operation, the return to normal of the bail 1247 may occur anytime between the 344° point in the machine cycle and the time at which the bevel gear 1278 has been rotated about 4° beyond the position it has at the instant the main drive shaft 126 completes its 360° machine cycling rotation. That results from the possibility of a 20° range of variation in the point at which the line-spacing clutch 1693, 1697 may become coupled because of the spacing of its clutch teeth. If the initiation of another machine cycle were to be prevented until the line-spacing bail 1247 returned to normal, a substantial pause would be caused between a machine cycle in which a line-spacing occurred and the succeeding machine cycle. However, means previously described prevents initiating of a machine cycle while the carriage is being opened, and the carriage, if open, is automatically closed in the early part of a machine cycle. Also, at the beginning of a carriage-closing operation, the front-feed paper chute and line finder assembly is locked 30 in its normal position by the latches 1167, 1168, so that there is no need to delay initiation of a further machine cycle while the line-spacing bail 1247 is returning to normal in a line-spacing operation commenced in the preceding machine cycle. The illustrated machine is provided with means to disable the interlock controlled by the line-spacing bail during a line-spacing operation, i.e., while the line-spacing clutch shaft 1694 is rotating and is out of its normal position.

35 The disk 1706 on the upper end of the line-spacing clutch shaft 1693 has a cam projection 2220 (Figs. 23 and 37) which, while the shaft 1694 is in its normal position, is engaged by an upturned lug 2221 on the leftwardly turned forward end of a latch lever 2222 which is pivoted on the stud 2192 below the slide 2216 and is urged clockwise by a tension spring 2223 connected at its right end to the lever 2222 and at its left end to the stud 2194. While the shaft 1694, disk 1706 and lever 2222 are in their normal positions, a notch 2224 with a cam inclined left side edge formed in the forward edge of the latch lever 2222 near its elbow, is behind a squared stud 2225 projecting downwardly from the underside of the slide 2216 to permit sufficient rearward movement of the slide 2216 to move the interlock projection 2219 under the lug 196 upon movement 40 of the front-feed paper chute and line finder

assembly upwardly and rearwardly from its normal position.

When the line-spacing clutch is engaged, the initial portion of the rotation of the shaft 1694 and disk 1706 removes the cam projection 2220 from contact with the lug 2221 and the spring 2223 rocks the latch lever 2222 clockwise to shift the notch 2224 leftward of the stud 2225 so that the slide 2216 is prevented from moving rearward as the line-spacing bail 1247 moves rearward. The forward edge of the elbow of the latch lever 2222 continues to block rearward movement of the stud 2225 and slide 2216 until near the very end of the line-spacing rotation of the shaft 1694, the cam projection 2220 of the disk 1706 engages the lug 2221 and cams the lever 2222 counterclockwise to its normal position.

Preventing closing of paper carriage while not properly conditioned for closing

Forwardly of its pivotal connection with the lever 2218, the slide 2216 (Figs. 23 and 37) has an upwardly and forwardly doubly bent end 2226 which normally engages a short upwardly extending arm 2227 secured at its lower end, as by welding, to a shaft 2228 rotatably supported in the front upward lugs 1263 of the gear box side plates 1261 and 1262. On the rightward end of the shaft 2228, rightward of the plate 1261, the hub of a short arm 2229 is pinned. A stud 2230 secured in the lower end of the arm 2229 is embraced in the slotted end of a downward arm on the rightward side of a yoke 2231 which is pivoted on the post 1270. A rearward arm on the right side of the yoke 2231 has a rightwardly turned flange 2232 positioned above the forward arm of the projection 1652 on the pawl 1648 which, as previously explained, must be in its upward position while being moved rearwardly to cause the carriage opening and closing clutch to be operated to close the carriage. A tension spring 2233 connected at its lower end to the stud 1494 and at its upper end to the rearward arm of the yoke 2231 urges the latter and thus also the arm 2229, shaft 2228 and arm 2227 clockwise so that, if the slide 2216 is in its rearward position in consequence of the front-feed paper chute and line finder assembly being out of normal position, the flange 2232 depresses the pawl 1648 to its lower position in which, if the pawl 1648 is moved rearwardly by depression of the carriage opening and closing key 1641, the carriage opening and closing clutch cannot be operated to close the carriage.

It will be apparent to those skilled in the art, that the embodiment above described by way of example may be modified in various respects without departing from the scope of my invention as defined in the appended claims.

I claim:

1. An accounting machine having a driving means, a printing mechanism, a paper carriage, a platen, means to hold papers in contact with said platen, said platen and paper holding means being mounted in said carriage for relative movement to open and close a paper insertion throat between them, paper guide means mounted on said carriage for movement, when said throat is open, to a retracted position to permit placement of a first paper around said platen, said guide means normally being positioned, when said throat is open, to guide inserted further papers into said throat so as to be held in print-receiving position between said platen and printing mechanism, a second paper holding means associated

with said guide means to hold said first paper against the platen, driving connections from said driving means to effect relative movement of said platen and first-mentioned paper holding means to open and close said throat, control means to cause said driving means to operate said connections, and means controlled by said guide means to prevent operation of said connections to close said throat when said guide means is in said retracted position.

2. An accounting machine having a driving means, control means to cause said driving means to drive the machine through cycles of operation, a printing mechanism, a paper carriage, a platen, means to hold papers in contact with said platen, said platen and paper holding means being mounted in said carriage for relative movement to open and close a paper insertion throat between them, paper guide means mounted on said carriage for movement, when said throat is open, to a retracted position to permit placement of a first paper around said platen, said guide means normally being positioned, when said throat is open, to guide inserted further papers into said throat so as to be held in print-receiving position between said platen and printing mechanism, a second paper holding means associated with said guide means to hold said first paper against the platen, driving connections from said driving means to effect relative movement of said platen and first-mentioned paper holding means to open and close said throat, means operable by said driving means in the initial portion of a machine cycle when said throat is open to operate said connections to close said throat, and means controlled by said guide means to prevent said control means from causing said driving means to drive the machine and said driving connections when said guide means is in said retracted position.

3. An accounting machine having a driving means, control means to cause said driving means to drive the machine through cycles of operation, a printing mechanism, a platen mounted for movement from a normal printing position to a retracted position in relation to said printing mechanism, connections from said driving means to said platen, manipulative means to cause said driving means and connections to move said platen from printing position to retracted position while the machine is not cycling, means operated from said driving means early in a machine cycle initiated while said platen is in retracted position to cause said driving means and connections to move said platen to printing position, and means controlled from a portion of said connections to disable said control means from causing said driving means to cycle the machine while said driving means and connections are moving said platen from its printing position to its retracted position.

4. An accounting machine having means to drive it through cycles of operation, a printing mechanism, a platen, a movable platen support, means operable by said driving means to move said support to carry said platen from a normal printing position to a retracted position and reversely relative to said printing mechanism, paper holding elements, tensioned springs yieldingly holding said elements in paper-holding cooperation with said platen when the latter is in normal position and urging said elements to move with said platen as the latter is moved away from its normal position toward retracted position, stop means to arrest such movement of said paper

holding elements in the latter portion of the movement of the platen from normal position to retracted position to effect separation of said elements from the platen to facilitate removal and insertion of papers therebetween, anchor means for said springs movably mounted on said platen support, and means moving said anchor means relative to the platen support to increase the tension of said springs in the final portion of the movement of said platen from retracted position to printing position to decelerate and cushion such movement of the platen, and reversely moving said anchor means in the early portion of the movement of the platen from normal printing

position toward retracted position to reduce the tension of said springs to said low value prior to arrest of said paper holding elements.
